[57] CLAIM

The ornamental design for a lawn cutter, as shown and described.

DESCRIPTION

FIG. 1 is a front, top and side perspective view of a lawn cutter, showing my new design;

FIG. 2 is a bottom plan view thereof; and,

FIG. 3 is a fragmentary sectional side view, partly in elevation, taken in the direction of the arrows along the line 3—3 in FIG. 2.

FIG. 3
